(57) **CLAIM**

The ornamental design for a keg shaped beverage container, as shown and described.

DESCRIPTION

FIG. 1 is an isometric view of a keg shaped beverage container including the ornamental design;

FIG. 2 is a front facing view thereof;

FIG. 3 is a side facing view thereof;

FIG. 4 is an opposite side facing view thereof;

FIG. 5 is a top view thereof;

FIG. 6 is a bottom view thereof;

FIG. 7 is an isometric bottom view thereof;

FIG. 8 is an isometric view of a second embodiment of a keg shaped beverage container including an ornamental opening mechanism;

FIG. 9 is a top view of the second embodiment; and,

FIG. 10 is an enlarged isometric view of the top portion of the second embodiment of the keg shaped beverage container.

The broken lines are included for the purpose of showing environmental portions of the keg shaped beverage container and form no part of the claimed design.
